UNITED STATES PATENT OFFICE.

THOMAS J. NAULTY, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

DOOR-OPERATING DEVICE.

No. 914,161.

Specification of Letters Patent.

Patented March 2, 1909.

Application filed May 4, 1898. Serial No. 430,967.

To all whom it may concern:

Be it known that I, THOMAS J. NAULTY, a citizen of the United States, residing in Philadelphia, Pennsylvania, have invented 5 certain Improvements in Door-Operating Devices, of which the following is a specification.

My invention relates to certain improvements in means for operating the doors of a 10 passenger car, particularly those at the forward end of the car for the exit of passengers, and my invention is especially adapted to the type of car in which the passenger pays the fare on entering the car.

One object of my present invention is to 15 so construct the door operating mechanism that it will be within easy reach of the motorman or other operator of the car, so that a slight movement of the operating mechanism 20 will either open or close the door.

A further object of the invention is to provide means for locking the door in either 25 of its two positions.

In the accompanying drawings:—Figure 25 1, is a sectional elevation illustrating the platform of a passenger car and showing my invention; Fig. 2, is a sectional plan view; and Figs. 3 and 4, are detached perspective views of the operating mechanism.

30 A is the platform of the car inclosed at one end by the ordinary vestibule B. At one side of the platform are two panels B' spaced apart to form a channel for the sliding door D which is arranged to close the exit doorway a. The opposite side of the car may be 35 closed by doors B² of any suitable construction; these doors are moved to allow free ingress and egress when the platform is at the rear of the car.

39 The door D is operated in the following manner:—Pivoted to a bracket c at the floor of the car is a handled lever C, this lever extends through a slot in a segment C' having a notch c' at each end. The handled 45 lever C extends through the floor of the platform and is connected by a rod c² to an arm c secured to a rock shaft E mounted in bear-

ings e' secured to the underside of the platform. Mounted on the end of the shaft E and extending into the space between the two panels B' is an arm E' having a slot e² at its upper end, and secured to the back of the door is a pin d' which extends into the slot e² in the lever E'.

When the lever is in the position illustrated in the drawings the door is closed and the lever C is held in position in one of the notches c'. By shifting the lever slightly to one side it is clear of the notch and by pulling it the door will be opened, then the lever will spring into the notch c² and hold the door open. When the door is in the closed position it cannot be forced open from the outside before the car comes to a stop.

65 By simply shifting the lever the door can be quickly thrown open to allow for the exit of passengers, and the mechanism for operating the door is within easy reach of the motorman so that he can operate the door 70 without leaving his post.

I claim:—

The combination of a car, a platform at one end of the car, a vestibule inclosing said platform and having a doorway at one side 75 of the platform, a sliding door arranged to close said doorway, an operating lever pivoted to the floor of the platform at the front and having one arm extending to such a height as to be grasped by the motorman, 80 the other arm of the lever extending through the floor, a shaft under the platform floor having two arms, one arm being connected to the door, and a rod attached to the other arm and to the lower arm of the operating 85 lever.

In testimony whereof, I have signed my name to this specification, in the presence of two subscribing witnesses.

THOMAS J. NAULTY.
